J. C. SHELLER

GAME

Filed July 25, 1927

INVENTOR
J. C. SHELLER
BY *Mum Leo*

ATTORNEY

UNITED STATES PATENT OFFICE.

JOHN C. SHELLER, OF MAYWOOD, ILLINOIS, ASSIGNOR TO JOHN F. SAYE, OF MAYWOOD, ILLINOIS.

GAME.

Application filed July 25, 1927. Serial No. 208,317.

My invention relates to improvements in games, and it consists in the combinations, constructions, and arrangements herein described and claimed.

5 An object of my invention is to provide a game in which a slideable bunker is provided for aiding in making the game more difficult to play.

10 A further object of my invention is to provide a game of the type described in which a trap is provided to further aid in making the game more difficult to play.

15 A further object of my invention is to provide a game of the type described in which both sides are used, and in which both sides must be used in order to complete the game.

20 Other objects and advantages will appear in the following specification, and the novel features of the invention will be particularly pointed out in the appended claims.

My invention is illustrated in the accompanying drawings, forming part of this application, in which

25 Figure 1 is a top plan view of the game, Figure 2 is a bottom plan view of the game, and

Figure 3 is a section along the line 3—3 of Figure 1.

30 In carrying out my invention, I provide a square casing 1 formed of walls having grooves 2 extending longitudinally therein and disposed at substantially the center thereof. A main partition 3 is centrally disposed in the casing 1 and is held against displacement, due to the fact that the edges thereof are received in the grooves 2. Two sets of auxiliary partitions A and B are disposed upon each side of the main partition

35 3. A wire mesh 4 is disposed over the set of auxiliary partitions A and is rigidly held in place by retaining strips 5. A wire mesh 6 is disposed over the auxiliary partitions B and is rigidly held in place by retaining strips 7. An opening 8 is provided in the wire mesh at one corner thereof for the insertion of a ball 9. The game is started by dropping the ball through the opening 8 and allowing the ball to pass through a compartment 10 past a spring catch or trap 11 which is disposed in the compartment 10.

40 As the ball passes to the opposite end of the compartment 10, it may pass into the adjacent compartment 12 through an open-

ing 13. By slanting the game, the ball will 55 roll through the compartment 12 to the end thereof which is formed by a short partition 14 where it will pass through an opening 15 to the opposite side of the main partition 3. As the ball passes through the opening 15, it is received in a compartment 16 between the auxiliary partitions B. By slanting the casing again to allow the ball to roll away from the opening 15, the ball will 60 pass to the opposite end of the compartment 16 where it may pass into a compartment 17 through an opening 18. Allowing the ball to pass through the compartment 17, the ball may pass through openings 19 and into a compartment 20. Passing the ball to the 65 opposite end of the compartment 20, the ball is allowed to pass through an opening 21 into a compartment 22. The ball then is rolled to the opposite end of the compartment 22 where it passes through openings 70 23 and into a compartment 24. Allowing the ball to roll to the opposite end of the compartment 24, it passes into a compartment 75 25 through an opening 26. In rolling down the compartment 25, the ball passes 80 through an opening 27 which is adjacent a short partition 28.

The ball is now back between the auxiliary compartments A within a compartment 29. The ball may pass from the compartment 29 through openings 30 and by a partition 31 to a compartment 32. In rolling along the compartment 32, the ball is guided through an opening 33 by a transversely extending partition 34 and into a compartment 90 35. The ball in passing to the opposite end of the compartment 35 may pass into a compartment 36 through openings 37 and by a partition 38.

The casing is then tilted allowing the ball 95 to roll to the opposite end of the compartment 36. Then by tilting the casing in another direction, the ball may pass through openings 39 to a compartment 40.

A movable bunker 41 which is closed upon 100 all sides, with the exception of a portion indicated at 42 which is arranged to align with the compartment 40, is slidably disposed at the ends of the compartments 10, 12 and 40. The normal position, that position taken by 105 the bunker when the game is started, is in alignment with the compartments 12 and 40. However as the casing is tilted to al-

low the ball to roll through the openings 39, the bunker, which slides freely, moves into alignment with the compartments 10 and 12. Therefore it is the purpose of the 5 player to prevent the ball from rolling back through the openings 39 and to slant the casing sufficiently to allow the bunker to move so that the open portion 42 is in alignment with the compartment 40. By tilting 10 the casing, the bunker may be moved to bring the ball into alignment with the opening 8.

There are several traps, these being compartments having an inlet and no outlet. 15 These traps are indicated at 43, 44, 45, 46 and 47 upon that side of the main partition between the auxiliary partitions A, and 48 and 49 upon that side of the main partition between the auxiliary partitions B.

20 I have indicated one route through which the ball may be passed in order to bring the ball back to the starting point. It is obvious that in this route I did not use the opening indicated at 50, but the ball may 25 be passed through the compartments and through the opening 50 which forms a different route in passing the ball from the starting point through the game and back again.

30 I claim:

1. A game of the type described comprising a casing, a main partition centrally disposed in said casing, auxiliary partitions disposed upon each side of said main partition and forming a plurality of compartments, transparent covers for said compartments, one of said covers having an opening therein for receiving a ball, said compartments being arranged to guide said ball therethrough and having openings for directing the ball from one compartment to another, said main partition having an opening therein in alignment with a compartment upon each side thereof, and a slideable bunker arranged to receive said ball for returning said ball to the opening in said cover.

2. A game of the type described comprising a casing, a main partition centrally disposed in said casing, auxiliary partitions for forming a plurality of parallel compartments disposed upon one side of said main partition and having passageways therethrough, auxiliary partitions disposed upon 55 the opposite side of said main partition for forming parallel compartments which extend at right angles to said first named compartments and having passageways therein, covers for said compartments, one of said covers having an opening therein arranged to receive a ball, and a spring catch arranged to allow the ball to pass thereby in only one direction, said ball being adapted to pass through a predetermined group of 60 the compartments between the auxiliary partitions, said main partition having an opening therein in alignment with compartments upon each side thereof for directing the ball from one side of said main partition to the other side thereof, said ball being adapted to be moved through predetermined groups of 65 the compartments and back into registration with the opening in the cover, and movable means adapted to interfere with the passage of the ball into registration with the opening in the cover, said means comprising a 70

titions, said main partition having an opening therein in alignment with compartments upon each side thereof for directing the ball from the one side of said main partition to the other side thereof, said ball being adapted to be moved through predetermined groups of the compartments and back into registration with the opening in the cover. 75

3. A game of the type described comprising a casing, a main partition centrally disposed in said casing, auxiliary partitions for forming a plurality of parallel compartments disposed upon one side of said main partition and having passageways therethrough, auxiliary partitions disposed upon the opposite side of said main partition for forming parallel compartments which extend at right angles to said first named compartments and having passageways therein, covers for said compartments, one of said covers having an opening therein arranged to receive a ball, a spring catch arranged to allow the ball to pass thereby in only one direction, said ball being adapted to pass through a predetermined group of the compartments between the auxiliary partitions, said main partition having an opening therein in alignment with compartments upon each side thereof for directing the ball from one side of said main partition to the other side thereof, said ball being adapted to be moved through predetermined groups of the compartments and back into registration with the opening in the cover, 80

movable bunker arranged to move into and out of registration with the opening in said cover.

5. A game of the type described comprising a casing, a main partition centrally disposed in said casing, auxiliary partitions for forming a plurality of parallel compartments disposed upon one side of said main partition and having passageways there-
10 through, auxiliary partitions disposed upon the opposite side of said main partition for forming parallel compartments which extend at right angles to said first named compartments and having passageways therein, covers for said compartments, one of said covers having an opening therein arranged to receive a ball, a spring catch arranged to allow the ball to pass thereby in only one direction, said ball being adapted to pass
15 through a predetermined group of the compartments between the auxiliary partitions, said main partition having an opening there-

in in alignment with compartments upon each side thereof for directing the ball from one side of said main partition to the other 25 side thereof, said ball being adapted to be moved through predetermined groups of the compartments and back into registration with the opening in the cover, and movable means adapted to interfere with the passage 30 of the ball into registration with the opening in the cover, said means comprising a movable bunker arranged to move into and out of registration with the opening in said cover, said bunker being adapted to stop said 35 ball from moving into alignment with the opening in said cover when said bunker is in registration with said opening, said bunker being adapted to receive said ball when said bunker is out of alignment with the opening 40 in said cover and to be moved with said ball for bringing said ball into registration with the opening in said cover.

JOHN C. SHELLER.
